SMOKER'S PIPE

William Rubly, Indianapolis, Ind.

Application February 14, 1940, Serial No. 318,786

4 Claims. (Cl. 131—201)

This invention relates to a smoker's pipe and relates particularly to means for insuring a clean dry bowl in addition to providing a smoke filtering means so arranged that the filtering medium 5 may not be ignited from the bowl and at the same time may be easily filled and discarded.

These and other objects of the invention will become apparent to those versed in the art in the following description of one particular form 10 of the invention as illustrated in the accompanying drawing, in which

Fig. 1 is a top plan view of a pipe embodying the invention;

Fig. 2, a central, vertical, longitudinal section; 15 Fig. 3, a top plan view of the cleaner tube; Fig. 4, an end view of the tube on an enlarged scale;

Fig. 5, a top plan view of a modified form of the cleaner tube; and

Fig. 6, an end view of the modified tube.

Fig. 7 is a perspective detail view of a position of the modified form.

Like characters of reference indicate like parts throughout the several views in the drawing.

The bowl 10 of the pipe may assume any desired form but in any event it is provided with a floor 11 centrally sloping downwardly to the side thereof nearest the pipe stem. The bowl 10 is provided with a stem extension 12, herein shown 20 as being integral with the bowl part 10. This stem extension 12 is bored axially to form a comparatively large bore therethrough and so located that the upper inner end of that stem bore cuts through and opens into the lower end of the bowl 30 10 by a comparatively small hole 13. In other words the top of the bore through the extension 12 is a trifle above the lowermost part of the floor 11 in the bowl 10.

A mouthpiece 14 is made out of any suitable 40 material and is formed to have a cylindrical end 15 of a diameter that will permit it to engage frictionally within the bore of a tube 16. This tube 16 is preferably made out of a rigid material, such as metal, and has an external diameter approximating that of the bore in the extension 12. By inserting the tube 16 within the bore of this 45 stem extension 12, frictional engagement is had within that bore, particularly by that part of the tube 16 which surrounds the end 15 of the mouthpiece 14 so that the mouthpiece 14 may be removably secured in position and there maintained in the desired relation with the bowl 10.

The tube 16 is cut away ahead of the mouthpiece end 15, Figs. 2 and 3, to leave a longitudinal 50 opening into the tube. Referring to that form of

the tube as shown in Figs. 2 and 3, in cutting away the upper part of the tube 16, a tongue 17 is left and given a periphery that will cause the tongue to fit snugly against the wall of the tube in an inclined position when that tongue is pushed 5 down into the tube to have its lower end come into contact with the floor of the tube. The tongue 17 thus forms a partition across the tube 16 including upwardly and outwardly toward the tube end. Then the tube is provided with a 10 groove 18 pressed downwardly in that part of the top side of the tube between the tongue and the end of the tube.

In practice, the mouthpiece 14 is removed to carry with it the tube 16. The tube 16 is then 15 filled through the top opening with any suitable filtering material. I find the ordinary pipe tobacco to be highly suitable for this purpose. In using such material, it is only necessary to fill the tube to the level of the side edges in the central 20 portion for the reason that the tobacco will swell up and fill the space thereabove to the full diameter of the pipe when the pipe is being used. The tube 16 is then inserted within the bore of the stem extension 12 to bring the mouthpiece 14 into 25 its proper position, as indicated in Figs. 1 and 2. The bowl 10 is filled with tobacco and smoked in the usual manner. The mouthpiece 14 carries the usual small diameter passageway 20 therethrough. Should all of the tobacco be consumed 30 within the bowl 10, the tobacco within the tube 16 will not become ignited from the last burning tobacco in the bowl 10 by reason of the fact that the tongue 17 serves effectively as a partition to form a small chamber in the front end of the tube 16 free of tobacco or filtering medium so that an air gap is thereby had between the pipe bowl 13 and the filtering medium within the tube 16. The groove 18 is of sufficient length to prevent 35 any substantial transfer of heat from the pipe bowl to the filtering medium.

Should for any reason the small hole 13 in the bottom of the bowl 10 become clogged, the mouthpiece 14 may be axially revolved so as to rock the tube end across the hole 13 and thereby clear 45 the hole. The tube 16 may be withdrawn by pulling out on the mouthpiece 14 and then the filtering material knocked out. Not only do the shoulders 19 at the sides of the groove 18 on the forward end of the tube 16 provide an excellent 50 means for cleaning the interior of the pipe, but they also may be used effectively by inserting the tube 16 downwardly within the bowl 10 to clean out the bowl itself.

Referring to the modified form of the filter 55

carrying tube as shown in Figs. 5 and 6, the forward end of the tube 16 may be formed in any other suitable manner to accomplish the same result as above indicated, such for example as by 5 cutting longitudinally through the top of the front tube portion and then bending one side of the tube downwardly and inwardly to form the retaining finger 21 which enters in a V-slot 22 formed in a plug 23 that serves as a partition 10 member in place of the tongue 17. The plug 23 preferably has its inner face sloped upwardly from the floor of the tube and forwardly. The plug is so proportioned in size as to leave a small chamber 24 in the front end of the tube as indicated in 15 Fig. 5. This form leaves a sharper cutting shoulder 25 at the front end of the tube. In any event, whether either form be employed, the filtering medium can be thrown out of the tube very readily by giving it a jerk to allow the material 20 to slide on up over the tongue 17 or the partition wall 23 so that no gouging or picking around in the tube 16 is required to clean it.

Should for any reason the tube 16 through use become loose within the bore of the stem extension 12, the free sides of the tube 16 between the front and rear ends thereof may be spread laterally so as to engage the wall of the bore more securely. Thus it is to be seen that I have produced a very simple yet effective pipe 25 construction, free of the usual difficulties, all without any complicated mechanisms or minute passageways, and while I have herein shown and described the invention in the one precise form, it is evident that structural variations may be 30 employed, such for example as varying the formation of the cutting end of the tube and the forward partition, etc., all without departing from the spirit of the invention and I, therefore, do not desire to be limited to that precise 35 form beyond the limitations as may be imposed by the following claims.

I claim:

1. For a pipe having a pipe stem and a bowl with a floor above the bore in the pipe stem 40 and a lower opening at the junction of the inner bowl wall and its floor for communication between the bowl and the bore of the pipe stem, a filter holding element consisting of a tube open at its rear end, and having a central top longitudinal opening intermediate front and rear tube 45 end portions, an imperforate wall across the front end portion of the tube closing off the major bore of the tube from its under side, and a depressed top part of the tube extending rearwardly longitudinally from the front end of the tube over said wall, said tube being of a diameter to fit snugly by its front and rear ends at least within that pipe stem bore whereby there is a smoke discharge passageway provided from said 50 bowl through said bowl opening downwardly onto and over said depressed tube part over said tube front wall and into the tube and out through its rear end portion, whereby a filtering medium may be placed in and removed from said tube 55 through its said longitudinal opening.

2. For a pipe having a pipe stem and a bowl with a floor above the bore in the pipe stem and a lower opening at the junction of the inner bowl wall and its floor for communication between the bowl and the bore of the pipe stem, a filter holding element consisting of a tube open at its rear end, and having a central top longitudinal opening intermediate front and rear 60

tube end portions, an imperforate wall across the front end portion of the tube closing off the major bore of the tube from its under side, and a depressed top part of the tube extending rearwardly longitudinally from the front end of the tube over said wall, said tube being of a diameter to fit snugly by its front and rear ends at least within that pipe stem bore whereby there is a smoke discharge passageway provided from said bowl through said bowl opening downwardly onto and over said depressed tube part over said tube front wall and into the tube and out through its rear end portion, whereby a filtering medium may be placed in and removed from said tube through its said longitudinal opening, said imperforate wall being spaced inwardly from the front tube end to be substantially at the rear end of said depressed tube part to leave an insulating chamber in the front tube end under said tube depressed part. 10

3. For a pipe having a pipe stem and a bowl with a floor above the bore in the pipe stem and a lower opening at the junction of the inner bowl wall and its floor for communication between the bowl and the bore of the pipe stem, a filter holding element consisting of a tube open at its rear end, and having a central top longitudinal opening intermediate front and rear tube end portions, an imperforate wall across the front end portion of the tube closing off the major bore of the tube from its under side, and a depressed top part of the tube extending rearwardly longitudinally from the front end of the tube over said wall, said tube being of a diameter to fit snugly by its front and rear ends at least within that pipe stem bore whereby there is a smoke discharge passageway provided from said bowl through said bowl opening downwardly onto and over said depressed tube part over said tube front wall and into the tube and out through its rear end portion, whereby a filtering medium may be placed in and removed from said tube through its said longitudinal opening, said depressed tube part being an integral part of the tube pressed from the tube into a trough-like shape. 35

4. For a pipe having a pipe stem and a bowl with a floor above the bore in the pipe stem and a lower opening at the junction of the inner bowl wall and its floor for communication between the bowl and the bore of the pipe stem, a filter holding element consisting of a tube open at its rear end, and having a central top longitudinal opening intermediate front and rear tube end portions, an imperforate wall across the front end portion of the tube closing off the major bore of the tube from its under side, and a depressed top part of the tube extending rearwardly longitudinally from the front end of the tube over said wall, said tube being of a diameter to fit snugly by its front and rear ends at least within that pipe stem bore whereby there is a smoke discharge passageway provided from said bowl through said bowl opening downwardly onto and over said depressed tube part over said tube front wall and into the tube and out through its rear end portion, whereby a filtering medium may be placed in and removed from said tube through its said longitudinal opening, said imperforate wall having a groove across its top edge, and said depressed tube part being carried down across said groove. 60

WILLIAM RUBLE.
